UNITED STATES PATENT OFFICE.

JOHN C. HULL, OF GASPORT, NEW YORK.

SPRAY-GUN.

1,221,861.

Specification of Letters Patent. Patented Apr. 10, 1917.

Application filed December 12, 1916. Serial No. 136,696.

To all whom it may concern:

Be it known that I, JOHN C. HULL, a citizen of the United States, residing at Gasport, in the county of Niagara and State 5 of New York, have invented a new and useful Spray-Gun, of which the following is a specification.

The device forming the subject matter of this application is a gun or nozzle, adapted 10 to be employed primarily for spraying fruit trees.

The invention aims to provide, in a device of this kind, through the instrumentality of a single rotary valve, means where- 15 by three important results may be brought about. These results are as follows: first, changes in the range of the spray proceeding from the gun; second, an expansion and a contraction of the spray proceeding from 20 the gun, to the end that a relatively narrow or a comparatively wide area may be treated; and third, a lessening of the quantity of liquid delivered, and a complete shutting off of the flow at the will of an operator.

Another object of the invention is to provide a spray gun in which the valve and its 25 actuating part are resiliently advanced, so that the valve may coöperate with the discharge element of the gun to effect a water-tight joint between the valve and the discharge element of the gun.

Another object of the invention is to provide, in a spray gun, a valve which has a movement on the actuating member, to the 35 end that the valve may coöperate with a relatively fixed part of the device, even though the said part of the device may be worn or somewhat irregular in form.

Another object of the invention is to provide novel means whereby through the instrumentality of a comparatively short barrel, ordinarily not more than one, two or three feet long, a spray may be applied to high trees, it being possible by a simple manipulation of the parts of the device to apply a fine mist or spray to low bushes or trees within close range, without dislodging the fruit therefrom, due to the impact of a heavy stream.

With the above and other objects in view which will appear as the description proceeds, the invention resides in the combination and arrangement of parts and in the details of construction hereinafter described 55 and claimed, it being understood that

changes in the precise embodiment of the invention herein disclosed can be made within the scope of what is claimed, without departing from the spirit of the invention.

In the accompanying drawings:—

Figure 1 shows in longitudinal section, a spray gun constructed in accordance with the present invention, parts appearing in elevation;

Figs. 2, 3, 4 and 5 are diagrammatic end elevations wherein a part of the casing which is carried at the forward end of the barrel has been removed in order to show the relations existing between the ports of the valve and the ports in a relatively fixed part of the device, during operations of various sorts;

Figs. 6, 7, 8 and 9 are sectional views, corresponding respectively to Figs. 2, 3, 4 and 5, and illustrating the relations existing 75 between the ports in the valve and the ports in a relatively fixed part of the structure;

Figs. 10, 11, and 12 are diagrammatic views, illustrating, in a general way, the character of the stream produced when the valve is set, respectively, as shown in Figs. 6, 7 and 8;

Fig. 13 is a rear elevation showing the front plate which, constituting a part of the casing, is applied to the forward end of 85 the barrel of the gun.

The device forming the subject matter of this application preferably is made of metal throughout, with the exception of washers and the like, and includes a cylindrical barrel 1. At this point it should be noted that the device herein disclosed is to be distinguished clearly from structures of that kind which employ a long barrel which is thrust upwardly among the branches of the tree to be sprayed. In the present instance, owing to certain structures to be described herein-after, high trees can be sprayed from the ground and, accordingly, the barrel 1 ordinarily is not more than two feet in length, although this dimension may be departed from, the intention being to direct attention strongly to the fact that a short nozzle, capable for use from the ground, is provided.

A coupling 2 is attached to the rear end of the barrel 1, preferably by threading. The coupling 2 is provided with a forward chamber 3 and with a rear chamber 4 which is slightly smaller in diameter than the chamber 3. At its rear end, the coupling 2 is sup-

plied with a bore 5 which is of materially less diameter than the rear chamber 4, so as to provide an internal shoulder 6 within the coupling 2. The coupling 2 includes a lateral inlet 7 which may be threaded or otherwise adapted to receive a hose (not shown) to the end that the liquid which is to be sprayed may be supplied to the interior of the barrel 1. A packing gland 8 is threaded or otherwise secured to the rear end of the coupling 2.

The invention comprises a front plate 9 shown in rear elevation in Fig. 13. The front plate 9 preferably is threaded onto the forward end of the barrel 1, and when this course is followed, it will be found desirable to provide the front plate 9 with parallel edges 10, so that the front plate may be manipulated readily by a wrench. The front plate 9 has a forwardly presented boss 11 of less diameter than the body portion of the front plate. The numeral 12 denotes a head which, roughly speaking, is of cup-shape. The head 12 is provided with a polygonal portion 14, adapted to be engaged by a wrench, so that the head may be threaded onto the boss 11 of the front plate 9. In front of the polygonal part 14, the head 12 is of circular contour as shown at 15. The head 12 includes a forward end wall 16 provided with ports 17. These ports 17 preferably but not necessarily are oppositely disposed and are of parti-circular form, the end edges of the ports 17 converging toward the geometrical center of the end wall 16. A cap 18 is threaded onto the forward part 15 of the head 12. In the forward end of the cap 18 there is a relatively large opening 19 defining an inwardly projecting flange 20 retaining a plate 21 having a discharge orifice 22 which is of small size compared with the opening 19 in the cap. The numeral 23 denotes a washer abutting against the plate 21 and defining a chamber 24. When the cap 18 is threaded into place on the head 12, the washer 23 is bound against the end wall 16 of the head, and the plate 21 is bound between the washer and the flange 20 of the cap 18.

The numeral 25 denotes an actuating member which, for lightness, may be in the form of a tube, the actuating member 25 being journaled in the gland 8. A handle 26 is secured to the exposed end of the actuating member 25 in any desired manner, as shown at 27, the handle 26 constituting means for rotating the actuating member. Within the contour of the coupling 2, the actuating member 25 carries an abutment 28 which may be in the form of a cross pin inserted through the actuating member. A compression spring 29 surrounds a portion of the actuating member 25 and is located in the rear chamber 4 of the coupling 2. One end of the spring 29 abuts against the shoul-

der 6, and the other end of the spring engages the abutment 28 of the actuating member 25.

The numeral 30 denotes a valve, preferably in the form of a circular disk, mounted to rotate in contact with the rear face of the end wall 16 of the head 12. The valve 30 has ports 31 shaped like the ports 17 in the end wall 16 of the head 12, and of approximately the same size as the ports 17. The ends of the ports 31 are beveled as shown at 32, circumferentially of the valve 30. The valve 30 comprises a rearwardly projecting boss 33 having a recess 35 in which the forward end of the actuating member 25 is received. The boss 33 has a cross opening 36. A pin 34 or like securing device is mounted in the cross opening 36 and passes through the forward end of the actuating member 25. It is to be observed that the recess 35 is slightly larger in diameter than the actuating member 25, and that the opening 36 is slightly larger in diameter than the pin 34. As a consequence, the valve 30 is loosely mounted on the forward end of the actuating member 25. The utility of this construction will be made manifest hereinafter.

Generally considered, the operation of the structure is as follows. The liquid to be sprayed passes by way of the inlet 7 into the barrel 1, through the ports 31 in the valve 30, through the ports 17 in the end wall 16 of the head 12, into the chamber 24, and out through the discharge orifice 22 in the plate 21.

The spring 29 advances the actuating member 25 and the valve 30, so that the valve 30 maintains a liquid-tight contact with the rear face of the end wall 16 of the head 12. Because, as hereinbefore indicated, the valve 30 is loosely mounted on the forward end of the actuating member 25, the valve will coöperate properly with the rear face of the end wall 16, even though the end wall may be worn or disposed out of rectangular relation to the axis of the barrel 1.

The ports 31 in the valve 30 are small enough so that the beveled surfaces 32 of the ports can be housed behind the end wall 16 when the ports 31 of the valve and the ports 17 of the end wall 16 are coincident. The parts are shown thus arranged in Figs. 2 and 6. Under such circumstances, two streams are discharged into the chamber 24, through the aligned or coinciding ports 31 and 17. These two streams move forwardly in straight lines and impinge against the plate 21. The streams then are directed toward each other, and flow outwardly through the discharge orifice 22 in the plate 21. Under the circumstances above mentioned, the stream proceeds from the discharge orifice 22 in a long slightly tapered form, as indicated in Fig. 10. Such a stream has a long range, and may be used for spray-

ing a comparatively high tree. Owing to the fact that the streams passing through the ports 31 and 17 impinge against each other before they unite to form a single stream and pass outwardly through the orifice 22, the stream shown in Fig. 10, although having a long range, is withal in the form of a spray, and will not knock off or injure the fruit on the tree which is being sprayed.

Note Figs. 3 and 7. Through the instrumentality of the handle 26, the actuating member 25 and the valve 30 may be rotated slightly, until the beveled portions 32 of the ports 31 in the valve 30 are visible through the ports 17 in the end wall 16. When the valve 20 is disposed as shown in Figs. 3 and 7, the effective size of the ports 17 in the end wall 16 has been decreased. The two streams which are discharged through the ports 31 and 17 will, accordingly, be discharged with greater velocity than when the valve is disposed as shown in Figs. 2 and 6. Further, because the beveled faces 32 of the ports 31 are now exposed to the streams as the same pass through the ports 31 and 17, the two streams will be given a whirling motion within the chamber 24. Owing to this whirling motion, two results are produced. First, the quantity of liquid discharged is lessened. Secondly, the stream shown in Fig. 11 is made to flare more widely than the stream shown in Fig. 10, the range being decreased, and the area which is covered being enlarged.

Let it be supposed that the valve 30 is rotated still further, until the ports 31 in the valve 30 and the ports 17 in the end wall 16 appear as shown in Figs. 4 and 8. The whirling motion is still imparted to the liquid, the rotating velocity of the liquid is increased, more than when the parts are disposed as shown in Figs. 3 and 7, and the stream emanating from the orifice 22 is made to flare still more, as shown in Fig. 12.

Finally, if the valve 30 is rotated until, as indicated in Fig. 5, its ports 31 are entirely out of registration with the ports 17 in the end wall 16, then the flow is cut off entirely, as will be evident when Fig. 5 is compared with Fig. 9.

Generally stated, the structure forming the subject matter of this application possesses the following advantages; the operator may spray the highest trees while standing on the ground, it being unnecessary to ascend a ladder, or to use a long nozzle; the

invention includes a combined means for stopping the flow entirely, and for regulating the flow, this regulation consisting first in varying the range, secondly, in altering the character of the stream, so far as the quantity discharged is concerned, and third, in regulating the area to which the liquid is applied. At no time does the structure herein disclosed produce a heavy compact stream which, applied to fruit, would injure the same or dislodge it from the trees or bushes. A means, represented by the spring 29, is provided, whereby the valve 30 may be advanced yieldingly, and, since the valve is loosely mounted on the forward end of the actuating member 25, the valve will co-operate properly with the fixed element 16 against which it abuts.

For convenience in claiming the invention, the same may be mentioned as comprising a barrel 1 and a casing carried by the barrel, the casing including an inner member represented by the end wall 16 of the head 12, an outer member represented by the plate 21, and a rotary valve 30 co-operating with the inner member.

Having thus described the invention, what is claimed is:

A spray gun comprising a barrel; a casing carried by the barrel and including inner and outer members, defining a chamber, the outer member having a discharge orifice, and the inner member having ports discharging into the chamber and against the outer member beyond the periphery of the discharge orifice; a rotary valve co-operating with the inner member and having ports which move into and out of coincidence with the ports of the inner member when the valve is rotated, the ports of the valve including inclined surfaces imparting a whirling motion to the liquid proceeding through the ports into the chamber, the ports of the inner member and of the valve being of such a relative size that, at times, the inclined surfaces of the ports of the valve may be housed behind the inner member, thereby to permit the liquid to traverse the ports in straight lines toward the outer member.

In testimony that I claim the foregoing as my own, I have hitherto affixed my signature in the presence of two witnesses.

JOHN C. HULL.
